Primary Examiner — Janice Hallmark(74) *Attorney, Agent, or Firm* — Kilpatrick Townsend & Stockton, LLP(57) **CLAIM**

The ornamental design for a tower air movement device, as shown and described.

DESCRIPTION

FIG. 1 is a perspective view of a tower air movement device, showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the figures are presented for the purpose of illustrating various portions of the tower air movement device, and form no part of the claimed design.
